Application November 10, 1936, Serial No. 110,027.
Renewed February 26, 1938. In Denmark July
8, 1936

5 Claims.

(Cl. 20—4)

The present invention relates to partition walls, especially light sound-insulating partition walls.

The invention has for its object to provide a new and improved partition wall combining great 5 lightness with a high insulating power.

A further object of the invention is to provide a wall of this kind that is easy and cheap to build, and easily can be erected and connected to the ceiling and floor in the rooms in which it is to be 10 placed.

The two principal forms of sound are air sound, which is propagated by oscillations in the air, and body sound which is propagated as oscillations in solid bodies. Body sounds may further occur as 15 rapping sounds, conduction sounds or as vibrations. Out of these sound forms generally only air sounds can be heard directly, while body sounds will easily be converted into air sounds and, as such, be propagated to the ear.

20 The sound-insulating properties of a partition are mainly contingent on the air-tightness of the partition and of the ability of the wall to weaken the conduction sound. Air sound finds its way through the smallest fissures. When air waves 25 hit a wall, a part of the air sound will be converted into conduction sound, which is partly absorbed and partly converted into air sound at the opposite wall surface. In the room in which the sound is generated, the air particles will also 30 accute the partition dynamically, in such a manner that the wall acts as a membrane, so that the air sound on one side of the wall will produce air sound at the other side of the wall. This membrane effect decreases with the increasing lateral 35 stiffness and increasing weight of the wall.

In order to provide a partition wall combining great lightness with a high sound-insulating power, the partition wall according to the invention is built in such a manner that it consists of 40 two outer plates and a central plate placed between the latter with intermediate spaces and fitted with bracing members so as to obtain lateral stiffness, the said central plate being connected to the two outer plates by means of connecting units that are mutually separated by sound-insulating intermediate layers. Hereby the advantage is attained that the outer plates, in combination with the central plate, to a great extent impede the direct passage of air sound, 45 because the latter has to pass through three plates between which there are spaces filled, perhaps wholly or partly with sound-absorbing material. Further, the passage of conduction sound, or the conversion of the same into air sound at the outer 50 plates, will be impeded in that the conduction

sound in one outer plate, in order to reach the other outer plate, has to pass the connecting members between the outer plates and the central plate, which connecting members, as mentioned above, are mutually separated by sound-insulating intermediate members, i. e. members of plastic nature in which the sound energy is partly annihilated. 5

It is especially suitable to produce the central plate by building the same from laterally stiff 10 sections which preferably should be joined in such a manner, with the use of sound-insulating interposed layers, that body sounds cannot easily pass from one section to the other one.

The invention is illustrated by way of example 15 on the drawing in Figs. 1 and 2, in two constructions in horizontal section. The invention, however, is not limited to the constructions shown on the drawing.

The invention is rendered practicable partly 20 by dividing the partition into two outer plates 1, 2 and a central part 3, each of which is as impermeable to sound as possible, and partly by making the central part 3 from laterally stiff sections 4, 5, 6 in Fig. 1 and 7, 8, 9 in Fig. 2, insulated 25 from one another in oscillatory respect by intermediate layers of plastic strips 10, and partly by attaching the outer plates of each side, to every other one (4, 6 in Fig. 1 and 7, 9 in Fig. 2) or to 30 still fewer of the sections of the central part, in such a manner that one of the outer plates does not come into direct contact with the sections to which the other outer plate is attached, or vice versa. 35

In Fig. 1, the central part 3 is made alternately from H-shaped sections 5 and T-shaped sections 4 and 6. The stems of the last mentioned sections point alternately to the right and left of the longitudinal direction of the partition, and 40 they support the outer plates 1 and 2 which are nailed or screwed to the free vertical edges of the stems, as shown at 11.

In Fig. 2, the central part 3 is made alternately from symmetrical T-shaped sections 8 and un- 45 symmetrical T-shaped sections 7 and 9. The flanges of the last mentioned sections are displaced alternately to the right and to the left side of the longitudinal direction of the partition, and they support there the outer plates 1 and 2 which are 50 nailed or screwed to the projecting vertical edges of the flanges.

In the flanges of the H-shaped profiles shown in Fig. 1, as well as in the flanges of all the T-shaped sections shown in Fig. 2, vertical suit- 55

ably deep and wide grooves are cut, and these grooves are engaged by the adjacent sections. The intermediate layers 10 are formed by strips of plastic material $\frac{1}{2}$ to $\frac{1}{8}$ inch thick and consisting, for instance of lead, asphalt felt, wax felt or the like, in such a manner that air-tightness is produced, without the plastic strip being thereby compressed too much.

In order to pass through the central part 3 to the other outer plate 2, any conduction sound produced in one of the outer plates 1 of the partition must pass one or more of the plastic members 10 in which nearly the entire oscillation energy is consumed in doing plastic deformation work. The outer plates as well as the central part must also be insulated from the adjoining walls, ceiling and floor by means of plastic intermediate layers similar to those mentioned above, because without these layers the conduction sound may escape by these ways.

All the sections of the central part may be produced from artificial materials or from dry full-edged boards. Where the boards are nailed, strips of flooring pasteboard, felt, lead or the like should previously be inserted for the sake of tightness. In both figures, the sections are supposed to be produced from boards 4 inches wide and 1 inch thick. The stems of the T-shaped sections in Fig. 1 are also supposed to be made from such boards split lengthwise.

The outer plates 1 and 2 may be produced in a manner known per se, for instance from building plates or, from 4 by $\frac{3}{4}$ inch rough boards and plaster 12. Inside of the plaster-supporting boards 13, a layer of suitable material as shown at 14 is first applied, partly in order to increase the tightness, and partly in order to prevent the mortar deposited from penetrating between and behind the plaster-supporting boards and, thereby, from coming into contact with the insulated sections in the central part, whereby sound bridges might be produced. In the cavities between the outer plates and the central part, sound-absorbing substances may be inserted. Without deviation from the characteristic principle underlying the invention, the central part 3 may also be made from sections of other shapes than those shown in the figures. Considering, in Fig. 1, the stems of the T-shaped sections as bridge piers, the H-shaped sections 5 as suspended beams and the plastic members 10 as pin-connections, the system will be similar to the cantilever principle.

I claim:

1. A partition wall consisting of two outer plates and a central plate disposed between the latter with intermediate spaces and composed of laterally stiff sections mutually sound-insulated by means of intermediate layers of plastic strips, some of the said sections being in direct contact with one of the outer plates, while other ones of sections are in direct contact with the other outer plate, and some of the sections in the central plate are not in direct contact with the outer plates.

2. A partition wall consisting of two outer plates and a central member disposed between the latter with intermediate spaces and composed of laterally stiff sections mutually sound-insulated by means of intermediate layers of plastic strips, each of said sections consisting alternately of an H-shaped and a T-shaped part joined together, the T-shaped parts contacting the outer plates.

3. A partition wall consisting of two outer plates and a central member disposed between the latter with intermediate spaces and composed of laterally stiff sections mutually sound-insulated by means of intermediate layers of plastic strips, each of said sections consisting alternately of an H-shaped and a T-shaped part joined together, the stems of the T-shaped parts pointing alternately to the right and left of the central member, and being connected to the outer plates, respectively.

4. A partition wall consisting of two outer plates and a central member disposed between the latter with intermediate spaces and composed of laterally stiff sections mutually sound-insulated by means of intermediate layers of plastic strips, some of said sections being of an H-shaped form, and the rest of said sections of T-shaped form, the latter being adapted to alternately contact each of the two outer plates.

5. A partition wall consisting of two outer plates and a central member disposed between the latter with intermediate spaces and composed of laterally stiff sections mutually sound-insulated by means of intermediate layers of plastic strips, some of said sections being of a symmetrical T-shaped form, and the rest of said sections of an unsymmetrical T-shaped form, the latter being alternately arranged with respect to the former and adapted to alternately contact each of the two outer plates, respectively.

AAGE ALEX JACOBSEN.
